(57) **CLAIM**

The ornamental design for a pool basketball goal, as shown and described.

DESCRIPTION

FIG. 1 is a front perspective view of a pool basketball goal design showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view thereof;

FIG. 9 is a front perspective view of the pool basketball goal in a stretched state; and,

FIG. 10 is a rear perspective view of the pool basketball goal in a stretched state.

The broken lines in the figures illustrate portions of the pool basketball goal that form no part of the claimed design.

1 Claim, 10 Drawing Sheets
